UNITED STATES PATENT OFFICE.

WILLIAM G. WALTER, OF PITTSBURG, PENNSYLVANIA, ASSIGNOR TO
ATTERBURY & CO., OF SAME PLACE.

DESIGN FOR A DISH.

SPECIFICATION forming part of Design No. 18,358, dated May 29, 1888.

Application filed April 14, 1888. Serial No. 270,700. Term of patent 7 years.

To all whom it may concern:

Be it known that I, WILLIAM G. WALTER, a citizen of the United States, residing at Pittsburg, in the county of Allegheny and State of Pennsylvania, have invented and produced a new and original Design for a Tureen or Dish; and I do declare the following to be a full, clear, and exact description of the same, reference being had to the accompanying drawings, forming a part thereof.

Figure 1 is a view in perspective of my design. Fig. 2 is a longitudinal sectional view.

The leading feature of my design consists of a dish having an oblong body, the top or upper portion or cover of said dish representing a boar's head.

In the drawings, A is the lower part of the dish or turcen, which may be of any suitable form or configuration to correspond with the outline of the cover.

B is the cover, in the form of the upper portion of a boar's head, with the ears, eyes, snout, tusks, &c.

C are the ears, which project rearward and upward, forming handles.

What I claim is—

A design for a dish or tureen having the bottom or body A and a cover, B, representing the conventional configuration or shape of the upper portion of a boar's head emerging 30 from a garniture of leaves, as shown and described.

In testimony whereof I affix my signature in presence of two witnesses.

WILLIAM G. WALTER.
